W. S. PAINTER:
CONCRETE BUILDING.
APPLICATION FILED OCT. 27, 1919.

1,369,296.

Patented Feb. 22, 1921.

UNITED STATES PATENT OFFICE.

WALTER S. PAINTER, OF NEW YORK, N. Y.

CONCRETE BUILDING.

1,369,236.

Specification of Letters Patent. Patented Feb. 22, 1921.

Application filed October 27, 1919. Serial No. 333,436.

To all whom it may concern:

Be it known that I, WALTER S. PAINTER, a subject of the King of Great Britain, and resident of New York city, in the county of New York and State of New York, have invented certain new and useful Improvements in Concrete Buildings, of which the following is a specification.

This invention relates to concrete buildings, particularly to foundation blocks adapted to be formed of concrete in suitable molds on the building site or in the shop, and when set or duly hardened, to be placed in position ready to receive a superstructure. These blocks will be formed to receive and properly support molded wall blocks in foundations, as for instance wall blocks or slabs made according to my application for Letters Patent filed June 5, 1919, under Serial Number 302,053 and I propose to handle them with the apparatus described in my application Serial No. 302,054, filed June 5, 1909; they will preferably be sufficiently long for several of said wall blocks to be placed side by side, to rest thereon and are characterized by having recesses formed in their upper surfaces to receive the lugs located on either ends of the wall blocks. Holes may be cast in the surface of such foundation blocks in which will seat locating pins or studs extending from the under sides of the wall blocks.

Openings may extend through the course blocks, they being formed with flanges downwardly tapered to simplify the molding operation and lighten them to facilitate handling, said formation affording the necessary strength for the purpose of a firm and strong structural piece to receive wall slabs. These openings are filled with concrete and form wedge-shaped blocks which in conjunction with the pre-cast blocks transmits the superimposed load to the ground.

The blocks consist of longitudinal flanges connected together by end webs and transverse webs considerably thicker than the side flanges and adapted to support the superstructure of the vertically arranged wall blocks seating thereon. The length of the foundation blocks will equal the width of a plurality of wall blocks placed side edges abutting.

The invention also contemplates a corner block construction made to support extended wall corner strips to complete the structure.

An integral extension of the end web of the foundation block with the recesses extended at right angles is formed to meet the recess of the normal block, thus forming the corner with the end extension block. The wall superposed on the extended foundation block is likewise extended.

The accompanying drawings will now be described to more fully indicate the nature and construction of this invention.

Figure 1 is a plan view of a foundation block, broken away in places to facilitate illustration, and showing the wall block seated thereon.

Fig. 2 is a longitudinal section on line 2—2 Fig. 1.

Fig. 3 is a transverse section on line 3—3 of Fig. 2.

Fig. 4 is a perspective view of an end of a foundation block, showing more clearly the relation thereto of a wall block in erected position and

Fig. 5 is a plan of a block used at the corner of the building with a recess turned at an angle as hereinafter described.

The dimensions of the foundation block of this invention are such as to afford adequate supporting area when filled with concrete and forming the wedge-shaped block shown in Fig. 2 on suitably prepared ground and to facilitate its ready handling in being set in place.

The block with all integral parts, formed of a properly prepared concrete in suitable molds, consists of longitudinal side flanges 6—6 connected together by end webs 7—7 and transverse webs or supporting pieces 8—8, so spaced lengthwise of the block as to leave openings 9 of uniform length between the ends 7 and adjacent transverse web 8, and between the transverse webs. The width or thickness of the end webs 7 exceeds that of the flanges 6, and the intermediate transverse webs 8, are preferably about twice as thick as the end webs. The ends 7 and transverse webs 8 are so spaced that a wall block will cover the whole width of the end and one-half of the transverse webs 8 as indicated in Fig. 1.

The upper faces of the end webs 7 and transverse webs 8 are provided with recesses 5 to receive correspondingly shaped lugs 11 on the lower end of the wall blocks 12, as clearly shown in Figs. 3 and 4. The wall blocks are thus properly located in central positions on the foundation blocks, but as

a further means for holding the wall blocks 12 in place they are provided with dowel pins, which may be projecting ends of reinforcing bars or rods 13, arranged to fit into 5 holes 14 in the foundation block 6.

In setting the blocks at the corners of the structure, the blocks as shown in Fig. 5 may be employed to complete the course. A heavier end web piece with recesses 15 above 10 mentioned at right angle is made to complete the corner. This recess 15 will support a wall slab continued to the end of the course and is shaped to receive an extended wall block carried by the adjoining corner foundation blocks. The corner extension blocks 15 will be provided with means for properly locating and holding the corner wall thereon. The webs are cast with a beveled formation, the heavy part of the web being at the top 20 of the block as it would be used in the building with the thin part of the web at the bottom. Thus, the concrete placed in the open spaces becomes a wedge-shaped concrete block. As the pressure from the super- 25 structure is applied, it is transmitted to the earth over the entire area of the foundation

block through these wedge-shaped concrete blocks.

Having described my invention what I claim is:

1. A concrete form composed of concrete and adapted to receive a superstructure, such form consisting of a plurality of wedge-shaped cored spaces formed by tapered side flanges and tapered cross and end webs, the 35 cored spaces being filled with concrete to form a wedge-shaped concrete block.

2. A concrete form, composed of concrete adapted to receive a superstructure, such form consisting of a plurality of wedge-shaped cored spaces formed by tapered side flanges and tapered cross and end webs, such webs having recesses on their upper surfaces formed to receive counter projections on the under side of a wall block of said 45 superstructure, the cored spaces being filled with concrete, to form a wedge-shaped concrete block.

Signed at New York city, in the county of New York and State of New York this 50 25th day of October, A. D. 1919.

WALTER S. PAINTER.
